UNITED STATES PATENT OFFICE.

JOHN B. PRICE, OF WOLLASTON, MASSACHUSETTS, ASSIGNOR TO OSCAR ELSAS, OF ATLANTA, GEORGIA.

SEWING-MACHINE.

SPECIFICATION forming part of Letters Patent No. 527,288, dated October 9, 1894.

Application filed September 16, 1892. Serial No. 446,079. (No model.)

To all whom it may concern:

Be it known that I, JOHN B. PRICE, of Wollaston, county of Norfolk, State of Massachusetts, have invented an Improvement in Sewing-Machines, of which the following description, in connection with the accompanying drawings, is a specification, like letters and on the drawings representing like parts.

This invention has for its object to simplify and improve that class of sewing machines employed for uniting the ends of piece goods for dyeing, &c.

In my improved machine, the eye-pointed needle above the cloth, and the complementary stitch-forming mechanism below the cloth derive their step-by-step or feeding movement across the cloth by or from flexible drivers preferably in the form of sprocket chains connected to the independent carriages, in one of which carriages the needle bar, and in the other of which the complementary stitch-forming mechanism works, both said flexible drivers deriving their movement from a common actuator or shaft. Preferably the actuating mechanism for the flexible drivers will be so constructed as to enable the carriages referred to to be quickly drawn back into their normal or starting position after the completion of each seam. The seam which I prefer to make is of the class known as a lap-seam, and to insure parallelism of the edges of the overlapped cloth to be stitched, I have devised and combined with the work-support of the machine a novel cloth-cutting device operating to cut the cloth transversely while clamped and before the stitching of the seam has been started. This cloth cutting device comprises a blade, and an arm having a foot and connected to a cutter-head, the latter being provided with an operating rod. The blade works in a longitudinal groove in a bar located along one edge of the work support and constituting a part of the clamping mechanism and a clamping bar having a longitudinal slot to guide the cutter-head, co-operates with said grooved bar to clamp together two edges of the material to be stitched, all as I will proceed now more particularly to set forth and claim.

By arranging the cloth cutting mechanism or device at one edge of the work support

and parallel to the line of stitching to be made, it is possible to put one broad piece of cloth in position on the bed-plate with its selvage edges substantially at right angles to the line of the seam to be made, and then to put the free end of that piece of cloth into the clamp together with the end of the other piece of cloth to be stitched to it, the other piece of cloth lying over the clamping bar. When the two ends are in the position described, they may be cut off while the ends of the cloth are in contact, thus leaving two straight and parallel edges, so that when the clamp is again opened, the operator merely takes the end of the piece of cloth hanging over the clamping bar, raises it slightly so that it is laid as indicated in the drawings, upon the free end of the piece of cloth lying on the work-support, and the ends having been overlapped, they will cling together frictionally to thus aid the operator in moving the overlapped portion of the two pieces into position to be stitched, the operator, during such operation, pressing upon the two layers of cloth where the same are overlapped and pushing in the two pieces uniformly in the line of operation of the stitch-forming mechanism.

Figure 1, in front elevation partially broken away centrally to shorten the same, shows a sewing machine embodying my present invention. Fig. 2 is a partial vertical section enlarged looking to the right of the line *x*, Fig. 1. Fig. 3 is a sectional detail showing the gearing for rotating the needle-bar actuating-shaft. Fig. 4 is a detail of the clutch to rotate the actuating shaft intermittently; Fig. 5, a detail showing one of the two like sprocket wheels about which run the flexible drivers at the left-hand end of the machine, viewing Fig. 1; Fig. 6, a detail of the needle-bar-carriage, to show the end of the flexible driver connected to it; Fig. 7, a detail of the complementary stitch-forming device shown on a smaller scale in Fig. 1, said figure showing but part of the carriage with the plate attached to it carrying the loop detainer; Fig. 8, a modified form of complementary stitch-forming device; Fig. 9, a detail of the cloth-cutting device detached; Fig. 10, an under side view of the loop-detainer enlarged together with the bar; Fig. 11, a top view of the hook and loop

guard; Fig. 12, a detail of the stop lever and arm r^3 . Fig. 13, shows the roll-controller detached. Fig. 14, shows part of the hub f^6 in section with its spring pin. Fig. 15, shows the two pieces of cloth lapped one on the other to be stitched; Fig. 16 to 18, details of the clamp. Fig. 19, is a detail showing part of the carriage b with the adjustable dog r^{10} on rod r . Fig. 20, is a detail showing the junction of one of the flexible connections.

The frame-work shown consists essentially of a base portion A having an upright A' to support an overhanging portion A², the base being set upon suitable legs or stands A³. This frame-work is of peculiar shape, as will be described, and has guide-ways A⁵, A⁶, see Fig. 2, to receive respectively the sliding carriages a, b, the former carrying the needle-bar a', and the latter, the complementary stitch-forming mechanism to be described which co-operates with the needle to form a stitch. These carriages a and b will in practice have at one edge a gib b⁸ of a shape to fit the guide-ways referred to, and preferably these gibs will be adjustably secured to the carriages by screws, as b², b³, best shown in Figs. 1 and 8, the contacting faces of the gibs and carriages being made wedge-shaped or beveled as in Fig. 8, so that by turning the screws b² in one or the other direction, as may be necessary, the gib may be adjusted longitudinally with relation to the carriage with which it co-operates to take up any lost motion or wear between the carriages and the grooves in the frame-work in which they slide in operation, withdrawal of the gib after withdrawing the shaft as hereinafter described and after opening the chain by the right and left hand nut 43 enabling a carriage to be readily removed. The frame-work has suitable bearings for a main or power shaft B, provided with a suitable fast and loose pulley B', B², and for suitably rotated shafts B³, B⁴. The main shaft has fast upon it a gear B⁵ which engages respectively the gears B⁷ and B⁸ fast respectively on the shafts B³ and B⁴, the latter shafts being rotated from the gear B⁵, the shaft B⁴, see Fig. 1, having, however, attached to it by a suitable set screw w⁴ a collar w⁵, said collar preventing longitudinal movement of the said shaft during the reciprocation of the carriage b. The shaft B³ has a like collar w¹⁰ to prevent it from sliding longitudinally.

The shaft B³ is grooved longitudinally, as at a², to receive a spline a⁸, see Fig. 3, connected to a toothed gear a⁹ surrounding said shaft loosely, said gear being embraced by a part of the carriage a, so that as the said carriage is moved longitudinally, as will be described, the said gear a⁹ is slid upon the shaft B³ and is rotated in unison with it. The gear a⁹ meshes with and rotates a gear a⁴, fast upon a needle-bar-actuating shaft a⁵, said shaft being mounted in bearings in the carriage a, and having at its front end suitable or usual cams, links, or devices, to reciprocate vertically a needle-bar a', having at its

lower end an eye-pointed needle a⁶, provided with a thread a⁷ acted upon by a suitable tension device a⁸ and taken from a suitable spool a⁹ on a suitable stand a¹⁰.

The carriage b has suitable bearings to surround the shaft B⁴ and between portions of the carriage, but feather-keyed to said shaft B⁴, is a cam b⁴, which while it is rotated by the shaft B⁴, is free to slide longitudinally thereon, said cam receiving in its groove a suitable roller or other stud 2 connected to a lever b⁶ pivoted at its lower end upon the said carriage.

The lever b⁶ actuates the stitch-forming mechanism complementary to and co-operating with the needle a⁶ to form a stitch.

The under stitch-forming mechanism or complementary stitch-forming mechanism may be either of the single thread, or of the double thread variety, I having illustrated it in Figs. 1 and 7 of the single thread variety.

In Figs. 1 and 7 the lever b⁶ carries at its upper end a device having a hook c to enter the loop of needle thread, said hook having moving and co-operating with it a loop-guard c', also fastened to said lever, said guard having a projection to enter a slot in the lever, the guard being soldered to one part of the lever. This hook enters the loop of needle thread when moved to the right viewing Figs. 1 and 7, and holds said loop while the needle rises, the said hook being suitably shaped at its under side to carry the loop of needle thread entered by it to the left when the hook is moved in that direction to retire from the loop, the movement of the hook to the left, viewing Figs. 1 and 7, aiding in spreading the loop for the entrance into it of the needle at its next descent through the material. The guard c' has a projection c², which, as the free end of the hook c retires from the loop of needle thread, enters said loop and in the further movement of the hook to the left carries the loose loop along with it and leaves the said loop at the front end of the loop detainer t, see Fig. 10, said loop detainer being a narrow plate located at one side of the needle hole t² in the plate t², a portion, as t²¹, of the said detainer crossing the said needle-hole. The detainer shown in Fig. 10 is adapted for use in a machine having two needles carried by the same needle bar, one of the arms projecting forward from the portion t²¹ co-operating with the loop of needle thread taken from one needle. The needle descends close to the edge of t²¹, said edge serving to arrest the new loop of needle thread as the hook in its movement to the right, enters and spreads said loop. This loop detainer also serves the purpose usually served by the throat plate, but herein said detainer is fixed to and so as to move with the carriage b during the stitching operation, said detainer traveling below the slot between the work supporting plates g and g' and being preferably a little wider than said slot.

In Fig. 8, the carriage *b* has attached to it by screws *e*, a shuttle race-plate *e'* adapted to receive a suitable shuttle carrier *e''* in which rests a shuttle *e'''* provided with thread, and the under stitch-forming mechanism, shown in Fig. 8, may be quickly substituted for the under stitch-forming mechanism shown in Figs 1 and 7, as a single or a double thread stitch is desired, that depending upon the particular work to be done. To effect this change, I first withdraw the screw *w⁴* to loosen the collar *w⁵* on the shaft *B⁴*, then take out the screws *e*, remove the screw forming the pivot for the lever *b⁶* and draw the shaft *B⁴* laterally out from the cam *b⁴*, such movement of the shaft permitting the said cam to be removed from the carriage. This done, I supply to the carriage a cam 201 and a lever 200 to be actuated by it, and put the shaft back through the said cam and fasten the collar. These two carriages *a*, *b*, are independent each of the other and each slides upon its own guides or tracks, but to sew properly these independent carriages must be moved in unison across the cloth, their movement being greater or less according to the length of the stitch to be made.

The carriage *a*, has connected to it in suitable manner the opposite ends of a flexible driver *f*, while the carriage *b* has in like manner connected to it the opposite ends of a flexible driver *f'*, these drivers, for the best results, being preferably in the form of sprocket chains deriving their movement from sprocket wheels *f²*, *f³*, respectively on an upright shaft *f⁴* sustained in suitable bearings in the part *A'* of the frame, said flexible drivers passing around like sprocket wheels *f⁵*, only one of which is shown in Fig. 5, suitably mounted on suitable studs supported by the frame-work at or near, in this instance, the left-hand end of the machine. In order that the step-by-step or feeding movement of these carriages may be measured to a nicety according to the length of stitch desired, I have provided a feed device to co-operate with the upright shaft *f⁴*, and this feed device is preferably of the variety known as a friction clutch feed, which I will now describe. The shaft *f⁴* has fast upon it a suitable hub *f⁶* shown best in Fig. 4 cut away at suitable intervals to form pockets *f⁷* for the reception of suitable rolls or balls *f⁸*, each preferably acted upon by a pusher *f⁹*, shown as a rod, acted upon by a suitable spring *f¹⁰*. The pockets are of varying depth and the hub *f⁶* is surrounded by a ring *f¹²* having an ear *f¹³* which is connected operatively with a slide-bar *f¹⁴* having a frame *f¹⁵*, inside of which rotates the cam *f¹⁶* fast on the driving shaft *B*, the rotation of the said shaft and cam reciprocating the frame *f¹⁵* and rod *f¹⁴*, to cause the ring *f¹²* to be moved in one and then in the opposite direction, the movement of the said ring in the direction of the arrow in Fig. 4, causing the said rolls *f⁸* to be carried into the smaller portions of the pockets *f⁷*, the

springs *f¹⁰* keeping the said rolls in contact with the hub and the ring, so that the rolls forced into the pockets serve to grasp frictionally the hub *f⁶*, and effect the rotation of the upright shaft *f⁴* and its attached sprocket wheels, the sprocket chains moving the carriages carrying the stitch-forming mechanism.

By the employment of a friction clutch feed in connection with the sprocket wheel shaped to actuate the flexible drivers, I may effect just the proper length of feed and may accomplish much better work than though a screw were used to effect the relative change of position of the stitch-forming mechanism and the work-supporting plates *g*, *g'*.

The machine has been provided with a stop rod *r* jointed at one end to an arm *r'* of a rock shaft *r²* extended horizontally to the rear of the frame and provided, see Figs. 2 and 12, with a second crank arm *r³* secured thereto by a pin *r⁴*, said arm being bifurcated at its outer end for the reception of the lower end of the stop lever *r⁵* pivoted thereto at *r⁶*, the upper end of said lever having an open notch, see Fig. 12, to embrace a feed-regulating device *r⁷* shown as a screw turned into the bar *f¹⁴*, said screw being also passed loosely through the ear *f¹³*, the rotation of said screw to withdraw it increasing the distance between the outer or free end of the bar *f¹⁴* and the washer *r⁸* on the said screw. The greater this distance the less the length of stitch, this being due to the lost motion, for it will be obvious that the washer *r⁸*, the farther it is distant from the end of the bar *f¹⁴*, the less distance it will move the ring in the direction opposite the arrow in Fig. 4. The stop lever during the stitching operation is moved with the bar *f¹⁴*, a spring *r⁹* surrounding the said bar acting to keep the ear *f¹³* against the upper end of said lever. The rod *r* has clamped upon it, see Figs. 1 and 19, a collar *r¹⁰*, shown as split and as having a screw *r²⁰* by which to tighten it in place on said rod. As the carriage *b* completes its movement in the direction of the length of the seam, or to the left viewing Fig. 1, it strikes the said collar and moves the rod *r* longitudinally, causing it, acting on arm *r'* of rock-shaft *r²*, to turn said rock-shaft and with it the slotted stop lever *r⁵*, the latter being moved laterally away from the rod *f¹⁴* connected to the reciprocating frame *f¹⁵*, said rod being passed through the ear *f¹³* of the clutch ring *f¹²* of the clutch feed. After the removal of the stop lever *r⁵* away from the rod *f¹⁴*, all further movement of the ring will be stopped, and consequently the feeding movement of the carriages carrying the stitch forming mechanism will be arrested. This withdrawal of the lever creates so much lost motion as to suspend or stop the rotation of the shaft *f⁴* and consequently the feeding movement of the carriages *a* and *b*. A spring 36 acts normally to throw the stop lever toward the feed-regulating device. The seam having been

completed, it is desired to draw the carriages *a* and *b* back quickly to their starting point. To do this I have provided a roll-controller *s*, see Figs. 2 and 13, said roll-controller consisting of a ring-like plate surrounding the shaft *f*⁴ loosely just above the clutch, said roll-controller having a series of pins or projections, as 30, which enter the pockets occupied by the rolls *f*⁸, the partial rotation of the 10 said roll-controller by hand causing the said pins to act on the said rolls and hold them back in the enlarged ends of the pockets in the clutch, so that the hub *f*⁶ may be readily turned in the then stationary ring *f*¹², this being done by rotating the shaft *f*⁴, by, it may be, a suitable crank *f*²⁰ see Fig. 1, applied to the upper squared or slabbed end of said shaft, this rotation of said shaft in its backward direction enabling the sprocket wheels thereon 20 through the sprocket chains to quickly draw back the carriages *a* and *b* without actuating the stitch-forming mechanism to form stitches. The hub *f*⁶ of the clutch has two spring-supported pins 31, one only shown, see Fig. 14, and the under side of the roll-controller has four countersinks as 32, see Fig. 13, made in pairs, and these two pins enter one or the other of the countersinks of each pair according to the position in which the 30 operator leaves the roll-controller.

The stop lever has at its lower end a positioning screw 33, the inner side of the head of the said screw being kept in contact with the arm *r*³ by a spring 34 when the said stop lever is disengaged from the feed-regulating device *r*⁷. This screw and spring act to keep the stop lever in proper upright position, so that when the rod *r* is to be moved to effect the re-engagement of the stop lever with the 35 feed regulating device *r*⁷, the carriages having been returned into their normal positions, there-engagement may be effected accurately.

The cloth to be stitched together rests on the work supports *g*, *g'*, parallel plates, with 45 a space, see Fig. 2, between them for the needle to move in, the plate *g'* being attached to a bar *g*², in practice connected at each end to suitable ears of the frame-work by set screws *g*³. The outer face of the bar *g*² is shown as provided with a longitudinal groove 50 for the passage of a blade *h*, see Fig. 9, and an arm *h'* having a foot *h*², said arm being connected to a cutter-head *h*³ attached to a rod *h*⁴, said cutter-head being guided in a slot 55 *h*⁵ in a clamping bar *h*⁶ having arms *h*⁷ attached to a rock-shaft *h*⁸ mounted in suitable bearings in the frame, said rock-shaft having other arms *h*⁹ connected by links *h*¹⁰ with arms *h*¹² of a second rock-shaft *h*¹³ having a 60 handle *h*¹⁴, the turning of which enables the clamp frame to be moved toward or from the outer side of the bar *g*² as when the ends of the cloth are to be clamped to be cut transversely by the knife, or to be opened to remove the trimmed cloth and overlap their 65 ends to be stitched, as represented in the de-

tail Fig. 15, the ends previously trimmed straight, being substantially parallel.

In the modification Fig. 8, the shuttle face-plate has a throat plate *n*.

The carriage *a* has a suitable presser-bar *n'* and attached foot *n*².

The needle thread will and may in practice have co-operating with it any usual tension device or slack thread-controller or take-up.

The arm *A*² at its left-hand end is shown as steadied by a strut *n*⁴ pivoted at *n*⁵ on a part of the frame-work below the arm *A*². When the strut is turned down as in dotted lines Fig. 1, the cloth with its ends stitched together may be removed from the machine.

In preparing the cloth for sewing, the end of one piece will be led into the machine under the arm *A*² from the rear side of the machine, and laid down over the outer edge of the bar *g*², the clamp bar *h*⁶ being then away from it.

The end of the other piece of cloth will be led from the front of the machine over the clamp bar *h*⁶ and the clamp closed on the two ends, the cutter-head being in place in the slot *h*⁵ with the knife *h* at the left of the bar *h*⁶, viewing Fig. 1.

The operator will grasp the rod *h*⁴ and draw the cutter-head to the right, and in doing so the two layers of cloth will be caught at their selvage edges between the cutter-head and the foot *h*², and as the head is moved to the right the knife will cut the cloth smoothly. This done, the cloth is unclamped, and the end of the piece of cloth led in from the front is lifted out and laid on the cloth led into the machine from the rear, and both pieces are moved slightly to the rear to bring the parts to be stitched together, in correct position under the needle.

It is preferred to hold the cloth stretched in about the line of seam during the stitching operation, and to effect this, I have provided two clamps *w*, *w'*, each composed of jaws acted upon by a suitable spring 37 to keep pins, at the ends of the jaws, in the cloth, the said pins entering suitable holes as 38, in the plates *g*, *g'*, as shown in the detail Fig. 16.

The jaws referred to are jointed to blocks 39 suitably grooved at their sides to embrace the edges of and slide in the space between the plates *g*, *g'*.

For connecting the chains to the carriages, I prefer, as shown in Fig. 6, to provide each carriage with adjustable screw studs 40, one shown in Fig. 6, to which the end of the chain will be secured by a screw or rivet 41 when the stud has been properly adjusted. To enable the chains to be kept taut I prefer to provide each chain near the middle of its length with a right and left-hand threaded nut 43 to engage screw studs as 44, 45, jointed to the chain sections. See Fig. 20.

This invention is not limited to the exact form of clutch device to rotate the shaft *f*⁴ intermittently, as instead I might employ any

other usual or suitable devices to impart to the said shaft a step-by-step movement.

The loop detainer t , the shape of which is best shown in Figs. 1, 7 and 10, is attached to the under side of a short plate t^2 mounted upon ears t^3 , t^4 , of a block t^5 secured to the upper end of the carriage b , said ears being shown but partially in Fig. 7, the main body of the carriage and block being broken away to save space on the drawings. The plate t^2 is of a width to substantially fill the space between the edges of the plates g , g' and serve as a support for the under side of the material on which rests the presser-foot. The plate t^2 is provided with a needle hole, but said needle hole is elongated, this being necessary owing to the fact that the stitch-forming mechanism and said plate travel across the goods, the loop detainer t in this invention detaining the loop as required and letting the thread play in the long slot t^{22} in the throat-plate, this plan obviating the needle puckering the goods when a chain stitch is being made.

I desire it to be understood that the needle-bar may carry one or more needles if desired, and the hook be duplicated so as to make simultaneously one or more rows of stitches.

Having described my invention, what I claim as new, and desire to secure by Letters Patent, is—

1. In a sewing machine for sewing together the ends of pieces of cloth, it containing the following instrumentalities, viz:—a stationary work-support, clamps connected therewith to engage two pieces of material near the selvage edges thereof, and hold the same in place while the ends of the material are being stitched together, two parallel rotating shafts B^3 , B^4 , gearing to connect the same, a needle bar having a needle, a carriage in which said needle bar is mounted, a rotating shaft in said carriage and connected with and adapted to reciprocate the needle bar, a second carriage located below the work-support, a device therein to engage the loop of needle thread in the formation of a stitch, a cam carried by said carriage movable therewith and adapted to be rotated by the shaft B^4 , independent guide-ways for said carriages, a flexible driver for each of said carriages, a driven shaft with which said drivers are connected, and from which they derive motion, a main shaft, and adjustable connections between the said main shaft and driven shaft whereby the motion of such driven shaft may be varied to affect the length of stitch, substantially as described.

2. In a sewing machine, a work support; clamps to hold in place on said support the material, the ends of which are to be stitched together; a carriage provided with a needle bar; a needle in said bar; a carriage provided with stitch-forming mechanism complementary to the needle; guide-ways for said carriages; and two flexible drivers, one connected with each of said carriages, combined with a shaft hav-

ing sprocket wheels to engage and actuate said drivers, and a friction clutch device applied directly to and adapted to rotate said sprocket wheel shaft, substantially as described.

3. In a sewing machine, the combination of a carriage adapted to support and move part of the stitch-forming mechanism, guide-ways in which said carriage travels and means to take up wear between said carriage and its guide-ways consisting of a beveled portion of the carriage next adjacent one of such guide-ways and an adjustable gib interposed between the said beveled portion and the guide-way next adjacent thereto, substantially as described.

4. In a sewing machine, a work-support, a carriage provided with a needle-bar, a needle therein, a needle-bar actuating-shaft mounted in bearings in said carriage, a shaft B^3 grooved longitudinally, a movable toothed gear splined to said shaft, connections between said carriage and gear whereby the latter moves with the former, a toothed gear on the needle-bar actuating-shaft in mesh with the movable toothed gear, a carriage provided with stitch-forming mechanism complementary to the needle, guide-ways for said carriages, and two flexible drivers, one connected with each of said carriages, combined with a shaft having sprocket wheels to engage and actuate said drivers, a clutch applied directly to said sprocket wheel shaft, and means for actuating the clutch and thereby rotating said shaft, substantially as described.

5. In a sewing machine, a work-support, a carriage provided with a needle-bar, a needle therein, a needle-bar actuating-shaft mounted in bearings in said carriage, a shaft B^3 grooved longitudinally, a movable toothed gear splined to said shaft, connections between said carriage and gear whereby the latter moves with the former, a toothed gear on the needle-bar actuating-shaft in mesh with the movable toothed gear, a carriage provided with stitch-forming mechanism complementary to the needle, and including a lever mounted on said carriage, a cam to actuate said lever, a rotating shaft on which said cam is splined loosely and capable of longitudinal movement, guide-ways for said carriages, and two flexible drivers, one connected with each of said carriages, combined with a shaft having sprocket wheels to engage and actuate said drivers, and a clutch applied directly to said sprocket wheel shaft, and means for actuating the clutch and thereby rotating said shaft, substantially as described.

6. In a sewing machine, the following instrumentalities, viz:—a work-support; clamps to hold in place on said support the material to be stitched; a carriage provided with a needle bar; a needle in said bar; a carriage provided with stitch-forming mechanism complementary to the needle; guide-ways for said carriages; two flexible drivers, one connected with each of said carriages, an up-

- right shaft, as f^4 , provided with two sprocket wheels to impart motion to said flexible drivers; a clutch, one part of which is mounted on said upright shaft; actuating devices for said clutch, and a stop lever, combined with devices actuated by one of said carriages to effect the release of said stop lever and thereby arrest the movement of the clutch, substantially as described.
10. 7. In a sewing machine, the stitch-forming mechanisms, and slideable carriages upon which they are mounted, drivers for such carriages, the shaft f^4 , and means to connect the said shaft and drivers, the hub f^6 on said shaft, a surrounding ring, a series of rolls between the ring and hub, a bar, as f^{14} , provided with a feed-regulating device, and devices to reciprocate said bar, combined with a stop-lever normally in operative position
15. with relation to the said feed-regulating device during the sliding operation of the carriage, and means for moving the stop lever out of operative connection with the feed-regulating device, substantially as described.
20. 8. The combination, in a sewing machine, of a work-support having a longitudinal space for the operation of the stitch-forming mechanism, cloth-cutting mechanism consisting essentially of a bar located along one edge of
25. the work-support and parallel to the line of stitching, and provided with a groove for the passage of the cutting blade, a clamping bar adapted to cooperate with said grooved bar to clamp together transversely the two ends
30. of two pieces of material to be stitched, and having a slot to guide the cutter-head, a cutter-

head, a blade thereon and a connected foot, the blade being adapted to cut the cloth transversely while held in the clamp to thus insure uniform overlapping of the material to be stitched preparatory to the stitching operation, substantially as described.

9. In a sewing machine, the combination with the upper and lower complementary stitch-forming mechanisms, of the work-holding plates separated from one another in the plane of movement of the stitch-forming mechanisms and having holes along their parallel edges, combined with the cloth clamping and stretching devices consisting of spring-jaws supported upon blocks movable in the space between the plates and supported by such plates and having pins to engage the holes in such plates, substantially as described.

10. In a sewing machine, the stitch-forming mechanisms and slideable carriages upon which they are mounted, drivers for such carriages and the driving shaft f^4 , and its operating clutch actuating devices, said devices including a feed regulating device made as a screw, combined with a stop-lever, an arm on which it is pivoted, and a positioning screw and spring, as and for the purposes set forth.

In testimony whereof I have signed my name to this specification in the presence of two subscribing witnesses.

JOHN B. PRICE.
